UNITED STATES PATENT OFFICE.

ALEXANDER PAUL FINKENSIEPER, OF BROOKLYN, NEW YORK.

BOWL FOR WATER-CLOSETS.

No. 927,783.

Specification of Letters Patent.

Patented July 13, 1909.

Application filed August 25, 1908. Serial No. 450,141.

To all whom it may concern:

Be it known that I, ALEXANDER PAUL FINKENSIEPER, a citizen of the United States, and a resident of Brooklyn, in the county of Kings and State of New York, have invented certain new and useful Improvements in Bowls for Water-Closets, of which the following is a specification.

My invention relates to water-closets and more particularly to bowls for use with the old form of iron trap such as used in the systems of plumbing employed before the introduction of the present system wherein a washout closet is constructed as a unit.

The main object of my invention is to provide ready means whereby an old system of plumbing for water-closets employing flush-rim bowls may be provided with the advantages of the washout closet system without having to tear out the old piping and rip up the floor to install the new system.

A further object is to provide a detachable bowl, such as used with an iron trap, with means whereby the same will be kept clean and sanitary by preventing the soil from getting between the two members of the closet and remaining there to create an odor.

A still further object is to provide a washout closet that will be more accessible to repair than the one at present in use.

In the old systems employing a flush-rim bowl with an iron trap, the soil passed through the bowl and into the iron trap where it stayed until washed through the trap by admitting water into the bowl. No water was held in the bowl so that if any soil adhered to the sides of the bowl, the incoming water would seldom wash it away. Also the outlet neck of the bowl did not enter the water held in the trap, so that soil &c. could lodge between the junction of the bowl and trap, creating bad smells and rendering the entire closet unsanitary. These evils were corrected in the new system employing washout closets wherein the bowl and trap are constructed as a unit, but it is necessary to have the discharge or soil pipe, leading from the closet, below the floor, so that if desired to have the new and more sanitary system it was necessary to provide entire new stand-pipes and rip up the flooring to put it in. Also it is necessary to have joints under the floor in this new system, which are liable to break

and if they do break or leak it is expensive to fix them as the floor must be ripped up. Further in the washout closet it is necessary to put the vent below the trap which is not the proper place, the proper place being at the crown of the trap.

By practicing my invention it is possible to attain the advantages of the washout closet without having to rip out the old pipes, traps &c. which were employed with the flush-rim closet. Further, all joints are above the floor and the vent can still be located at the proper place, namely at the crown of the trap.

My invention consists in the combinations and arrangements of parts hereinafter more particularly described and then specified in the claim.

In the accompanying drawings Figure 1 illustrates diagrammatically the old system having my invention applied thereto. Fig. 2 is an enlarged vertical section through an iron trap having my invention applied thereto. Fig. 3 is a horizontal section taken on the line A A, Fig. 2.

Referring to the diagrammatic view Fig. 1, 1 indicates the floor of a structure in which the toilets are located and 2 indicates a stand-pipe through which the soil from the closet is carried to the sewer, while 3 indicates another stand-pipe through which the closets are vented.

The trap for the closet, indicated at 4, is constructed of iron and is provided with a single turn or bend in which a quantity of water 5 is held. The trap rests on the floor as shown and is connected to the stand-pipe 2 so that the contents from the trap or bowl will be discharged into said pipe. A pipe 6 connects at one end with the vent pipe 3 and at the other is tapped into the crown of the trap as shown.

11 indicates a bowl of porcelain provided with a dip 12 adapted to hold a quantity of water and also to receive the soil, the soil or other contents being washed out of the dip by forcing a stream of water into it in substantially the same manner that the ordinary wash-out closet is washed, which method is old and well known in the art. A pipe 13 formed in the side of the bowl 11 and preferably integral therewith, receives the contents of the dip 12 and discharges them into the trap 4, the pipe 13 being curved so that its outlet will be directly under the center of the bowl and fit into the trap. The outlet

end of the pipe or passage 13 is extended so that it enters the trap below the surface of the water held therein which prevents any dirty water or soil getting between the surface of the bowl and the sides of the flared end of the trap. The bowl is suitably supported on the flared end of the trap by a flange 14 resting thereon. The outer surface of the lower part of the bowl 11 is cone shaped and as shown in the section Fig. 6 fits closely all around the flared end of the trap while the discharge pipe or passage 13 is formed in one side and so curved that the discharge end will come directly under the center of the bowl so as to permit it to enter the trap 4.

The invention claimed is:—

In a water-closet, the combination with an iron trap provided with a flared end and

consisting of a single turn adapted to hold 20 water and a horizontal discharge, of a porcelain bowl, the lower part of which is cone shaped and adapted to fit within the flared end of said trap, a dip in said bowl adapted to hold a quantity of water and a discharge 25 pipe formed within said bowl and adapted to receive the contents from said dip, said pipe being formed within the cone shaped part of said bowl and curved to bring its outlet directly under the center of said bowl 30 and below the level of the water in said trap.

Signed at New York in the county of New York and State of New York this 19th day of August A. D. 1908.

ALEXANDER PAUL FINKENSIEPER.
